UNITED STATES PATENT OFFICE.

LUCAS RENFTLE, OF WARREN, OHIO.

WRENCH.

1,335,028.

Specification of Letters Patent. Patented Mar. 30, 1920.

Application filed April 26, 1919. Serial No. 292,900.

To all whom it may concern:

Be it known that I, LUCAS RENFTLE, a citizen of the United States, and resident of Warren, in the county of Trumbull and State of Ohio, have invented certain new and useful Improvements in Wrenches, of which the following is a specification.

The present invention relates to wrenches, and aims to provide a novel and improved implement of that character provided with novel swinging jaws so arranged as to separate to receive objects of different sizes therebetween, and connected to the handle or lever in such a way that when the handle or lever is swung to turn the nut or other object between the jaws, the jaws will be caused to tightly grip the object to prevent slipping.

A further object is the provision of a wrench embodying outer and inner jaws both pivoted to the shank or lever, with the arrangement of said lever and jaws being such that the jaws will be disposed parallel in their different positions and will be caused to tightly grip or clamp the object therebetween when the lever is swung in the corresponding direction.

It is also the object of the invention to provide such a wrench which is simple and inexpensive in construction, as well as being practical, serviceable and efficient in use.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawing, wherein:—

Figure 1 is a side elevation of the wrench with the jaws in their closest relation.

Fig. 2 is a similar view showing the jaws separated for gripping a larger object.

The wrench embodies a straight shank or lever 1 of suitable length, and a rocking or swinging jaw 2 at one end of said lever 1, said jaw extending transversely across the end of the lever, and having an inwardly extending ear 3 between its ends overlapping the lever and pivoted thereto, as at 4, so that said jaw can be tilted or swung to different angular positions.

The outer jaw 5 is also mounted for swing-

ing or tilting movement, and is longer than the inner jaw 2 and disposed parallel therewith outside of said inner jaw. This outer jaw 5 is carried by an arm 6, said jaw 5 extending at substantially right angles from the outer end of said arm which is disposed at one side of the lever 1. The inner end of the arm 6 extends at an angle toward the lever 1, as at 7, and is pivoted to said lever in the longitudinal center line thereof, as at 8, between the ends thereof a considerable distance from the pivot 4. In closed position the jaws both extend transversely across the longitudinal center line of the lever to opposite sides.

Thus, when the arm 6 is swung away from the lever 1, the jaw 5 will move away from the jaw 2, thereby separating the jaws, so that they can be applied to objects of different sizes, and at the same time, the jaw 2 can be swung or tilted so as to remain parallel with the jaw 5, as seen in Fig. 2. Furthermore, due to the arrangement, when the end or handle of the lever 1 opposite the jaws is swung (downwardly as illustrated) this will pull the arm 6 and jaw 5 with the lever, and the joint or pivot 4 between the lever and jaw 2 will tend to swing or move upwardly, so as to have a tendency to turn the jaw 2 toward the position shown in Fig. 1, thereby causing the object to be tightly gripped. In other words, when the jaws are swung toward one side, as seen in Fig. 2, and the handle of the lever 1 is swung, this will tend to swing the parts toward the position shown in Fig. 1, in order that the jaws will be moved toward one another with considerable pressure, so as to prevent slipping of the object therebetween.

The faces of the jaws and a portion of the arm 6 can be toothed as shown, especially when the wrench is used as a pipe wrench. Said jaws are elongated and their faces straight so as to be disposed parallel in various angular positions and to overlap to grip the object between them.

In order to maintain the jaws parallel, when this is desired, a link or rod 9 can be provided between the arm 6 and jaw 2, with its ends pivoted, as at 10, to said jaw 2 at 105 one end and to the arm 6 near the pivot 8. This rod or link will cause the jaw 2 and arm 6 to swing with the faces of the jaws always parallel. The pivots 10 are removable, in order that the link 9 can be detached 110

when not wanted, as a better gripping action can be obtained without this link, such as when using the device as a pipe wrench.

The wrench can be conveniently applied to the object, without the necessity of adjusting any of the parts, other than to swing the jaws apart, which can be done very easily and quickly, and there are no sliding parts or adjustments as in the ordinary wrench, 10 which require more or less time and work in making adjustments. In fact, the present wrench can be applied almost instantly to objects of different sizes, simply by swinging the jaws apart and then swinging the lever 15 after the object is between the jaws, which will cause the jaws to tightly grip the object without liability of the parts slipping.

Having thus described the invention, what is claimed as new is:—

- 20 1. A wrench comprising a straight lever having a handle at one end, an inner jaw pivoted to the other end of the lever to swing around said end and extending across the longitudinal center line of the lever to opposite sides, an arm extending along one side of said lever and having a portion at one end extending at an angle and pivoted to the lever substantially in said center line thereof a considerable distance from the inner jaw

between the ends of the lever, the other end 30 of said arm having an outer jaw extending at an angle therefrom beyond the inner jaw, and a longitudinal link connecting said portion and inner jaw at one side of the lever.

2. A wrench comprising a straight lever 35 having a handle at one end, an inner jaw pivoted between its ends to the other end of said lever to swing around said end and extending transversely across the longitudinal center line of said lever to opposite sides, an 40 arm extending along one side of said lever and having one end pivoted to said lever substantially in said center line a considerable distance from the inner jaw between the ends of the lever, the other end of said 45 arm having an outer jaw extending at an angle therefrom beyond the inner jaw, said inner and outer jaws having elongated straight faces to be disposed parallel in overlapping relation in various angular positions, and a longitudinal link for operatively connecting said inner jaw and arm at one side of the handle to maintain the faces of the jaws parallel.

In testimony whereof I hereunto set my 55 hand.

LUCAS RENFTLE.
